BLISTER PACKAGE

Hugh Horner, Merrick, N.Y., assignor to Chas. Pfizer & Co., Inc., New York, N.Y., a corporation of Delaware

Filed Feb. 11, 1965, Ser. No. 83,788

Term of patent 14 years

(Cl. D58—2)

Fig. 1.

Fig. 2.

Fig. 3.

Fig. 4.

FIG. 1 is a front perspective view of a blister package, showing my new design;

FIG. 2 is a side view of the blister package shown in FIG. 1;

FIG. 3 is a front perspective view of a blister package showing another embodiment of my design wherein the blister package includes a simulated cap having a smooth exterior;

FIG. 4 is a side view of the blister package shown in FIG. 3.

I claim:

The ornamental design for a blister package, as shown and described.
